RIVETING MACHINE

Hjalmar Thomason, Los Angeles, Calif.

Application June 3, 1937, Serial No. 146,211

10 Claims. (Cl. 218—2.1)

This invention relates to improvements in riveting machines such as those as are primarily designed for riveting brake linings to brake shoes, but which may be used for other purposes as well. The invention primarily concerns improvements in riveting machines of this character having automatic feeds.

An object of the invention is to provide an improved riveting machine susceptible of receiving and automatically feeding a large number of rivets of different sizes and to provide means whereby the operating mechanism of the machine can be easily and quickly cleared of rivets of one size and rivets of other sizes substituted therefor.

More specifically, an object of the invention is to provide a riveting machine wherein there is a track which feeds the rivets toward the work between the punch and anvil of the machine and a rotatable drum which receives the rivets and feeds them in proper position onto the track wherein there is a magazine associated with the drum which may or may not have a plurality of separate compartments that can be placed in communication with the drum, the magazine being rotatable so that in one position rivets may be fed therefrom into the drum and in an alternative position the rivets may be returned from the drum to the magazine without loss.

Another object of the invention pertaining to the objects above-mentioned, is to provide an improved drum construction which will facilitate clearing the drum of rivets to enable them to be returned to the magazine or its compartment.

With the foregoing and other objects in view, which will be made manifest in the following detailed description, and specifically pointed out in the appended claims, reference is had to the accompanying drawings for an illustrative embodiment of the invention, wherein:

Figure 1 is a partial view in side elevation of the improved brake lining machine, illustrating in dotted lines the position that the magazine may assume in emptying the drum in effecting a change of rivet sizes;

Fig. 2 is a partial view in side elevation of the rear of the machine;

Fig. 3 is a vertical section taken substantially upon the line 3—3 upon Fig. 1;

Fig. 3a is an enlarged partial section of the clutch shown in Fig. 3;

Fig. 4 is a horizontal section taken substantially upon the line 4—4 upon Fig. 3;

Fig. 5 is a vertical section taken substantially upon the line 5—5 of Fig. 3;

Fig. 6 is a partial view illustrating the shape

of one end of a guide associated with one of the drums of the machine and is a view as seen looking down at the top of the guide in a position substantially as shown in Fig. 5; and

Fig. 7 is a front view in elevation of the improved brake lining machine.

Referring to the accompanying drawings wherein similar reference characters designate similar parts throughout, the improved brake lining machine comprises a frame generally designated at 10 on which there is mounted a suitable anvil indicated at 11. In upper alignment with the anvil there is mounted on the frame a punch 12 adapted for reciprocating movement and connected by one or more links 13 to a forcing lever 14 which is pivoted at 15 on the frame. The forcing lever has its rear end connected to a draw rod 16 which can be pulled downwardly by any suitable mechanism (not shown) such as for example a foot treadle. When the draw rod 16 is pulled downwardly by the foot treadle the forcing lever 14 operates through links 13 and forces the punch 12 downwardly toward anvil 11 to force the rivet through the work and cause the anvil to roll the shank of the rivet and to form a rivet head on the bottom of the rivet. Draw rod 16 is normally urged into uppermost position such as by a spring (not shown).

The machine as illustrated, is capable of handling ten different sizes of rivets but it will be understood that by small changes in design a larger number or a smaller number of rivets may be accommodated by the machine.

A rotary shaft 17 extends transversely across the frame at the back thereof and near its top. On this shaft there are positioned bushings 18 and 19 and a cam follower 20 is pivoted for rotation on the inner ends of these bushings and is arranged in alignment with forcing lever 14.

The cam follower carries a roller 21 which is in engagement with the cam-shaped top surface of the forcing lever. Cam follower 20 is provided with a pivoted pawl 23 which engages a ratchet wheel 24 fixedly mounted on rotary shaft 17.

The purpose of this construction is such that when draw bar 16 is pulled downwardly to force the forcing lever downwardly in the process of riveting, the cam follower 20 may swing about shaft 17 as a center in a counter-clockwise direction from the position shown in Fig. 1. During this movement pawl 23 merely slips over the teeth on the ratchet wheel 24. When draw bar 16 is released and is elevated by the spring means not shown, the cam follower moves in a clockwise direction into the position shown in Fig. 1.

and during this movement pawl 23 engages ratchet wheel 24 and imparts rotational movement to shaft 17. The purpose of rotating shaft 17 is to rotate the rivet aligning drums 25 and 28 as will be later described.

On each bushing 18 and 19 there are positioned washers 27 and magazine supporting frames 28. The magazine supporting frames are rotatable on the bushings about the center of rotation of their respective drums. They are held thereon by means of nuts 29. The magazine supporting frames carry vertically disposed spindles 30 on which the magazines 31 are rotatable. They also carry hoppers 32. Each magazine as shown is divided into five compartments, the compartments illustrated in Fig. 4 being indicated at 33, 34, 35, 36, and 37. The outer walls of the compartments may be formed by glass windows 38 so that the quantity of rivets disposed in any compartment may be readily ascertained by looking through these windows.

A sliding plate 39 forms a gate which is urged by spring 40 into closed position. This gate is slidably mounted between the top of the magazine and the bottom of the hopper 32. By means of its handle 41 this gate may be opened so as to enable rivets placed in hopper 32 to drop into whichever compartment of the magazine is positioned beneath the hopper. On release of handle 41 the gate formed by sliding plate 39 is returned to closed position by spring 40. The gate is so arranged as to open the bottom of the hopper 32 and place it in communication with only one compartment, namely that compartment which is positioned immediately beneath the hopper. It will be understood, however, that by rotating the magazine any of its compartments may be selectively positioned beneath the hopper and that on opening the gate formed by plate 39, rivets placed in the hopper may be dropped into that compartment. In this way a single hopper may be used to deposit the rivets of all of the sizes desired into their respective compartments. A similar gate which is also spring-actuated into closed position is located beneath the magazine. This gate is formed by plate 42. On opening the bottom gate 42 the rivets in the compartment directly thereabove which is beneath hopper 32 can be dropped through an outlet 43 and discharged into the aligning drum 25. The aligning drum 25 is loosely mounted on shaft 17 but is operatively connected thereto by means of a suitable clutch. On the outer end of shaft 17 there is a ring 44 locked thereto and containing a spring retracted locking dog 45 the end of which can be forced against the action of the spring into an aperture 46 in the drum.

The head of the locking dog 45 is engageable by the inner face of a rotatable ring 47 which is urged inwardly by a spring 48. On its inner face, ring 47 has one or more recesses 49 into which the head of the locking dog is receivable to allow the spring to retract the locking dog from locking engagement with aperture 46 in the drum 25. In the position shown in Fig. 3 the locking dog 45 is retracted so that the drum 25 is disconnected from shaft 17. By rotating ring 47 so that the head on the dog 45 is forced out of the recess 49 the dog may be forced to enter aperture 46. In this way the clutch operatively connects drum 25 with shaft 17 so that the drum will be rotated in a step-by-step manner every time that draw bar 16 is lowered and raised.

The drum is of the general shape of a frustum of a cone with its large end disposed inwardly.

This large end is provided with a large number of approximately radial slots 50. The magazine supporting frame 28 forms a type of housing within which the large end of the drum rotates.

5 The large end of the drum is spaced from the vertical wall of this housing, as indicated at 51, and this space is sufficient to accommodate the heads of all of the sizes of rivets that may be placed in the magazine. The lengths of the slots 10 50 are such as to accommodate all lengths of the shanks of all rivet sizes that may be placed in the magazine.

A peripheral guide 52 is secured to and extends partly around the interior of the housing adjacent the periphery of the drum. The lower end of such guide 52 terminates at 52a adjacent the outlet opening 53 in the wall of the housing formed by the magazine supporting frame 28. The other end 55 of this guide extends diagonally 15 as shown in Fig. 6 from the vertical edge 55a to the opposite vertical edge 55b, this figure illustrating a view of the top end of the guide. A second guide 54 is secured to and disposed within the housing and located in the space 51, note 20 Fig. 3. The edge 54a of guide 54 thus forms a cord of the circle formed by the periphery of the housing. The upper end of edge 54a terminates at the edge 55b of the upper end of the peripheral guide 52. The upper edge 55 of the guide 52 is beveled as is the cord edge 54a of the guide 54 thus facilitating shifting of the rivets.

The outlet 53 discharges into the upper end of a track 56 formed by spaced rails defining a slot 57. The magazine frame 28 which is rotatable 35 about the axis of rotation of the drum 25 is normally locked in the upright position shown in full lines of Fig. 1. This is accomplished by means of a spring-actuated plunger, the handle of which is indicated at 58, Fig. 7. Withdrawal 40 of this plunger releases the magazine frame which is then free to rotate on bushing 18 and may be swung into the dotted line position shown. The purpose of such a construction is to enable the emptying of the drum of rivets therein and thus clear the rivets from the drum which are to be returned back to their proper compartment in the magazine. For example, in the position shown, if compartment 33 of the magazine has 45 been opened to deposit a supply of rivets in the drum which in turn, are fed by the drum into slot 57 of the track and it is desired to empty the drum of this size of rivets preparatory to using rivets of a different size, the magazine is unlocked by means of plunger 58 and swung into 50 the dotted line position. In this position the opening 43 in the magazine frame will be swung into a position near the bottom of the drum and on rotation of the drum the rivets that may be in the drum will be caused to spill therefrom through opening 43 and back into the compartment of the magazine. The beveled edge 55 tends to sweep the rivets toward this opening and guide 54 cooperates therewith in lifting rivets out of slots 50 in the drum. There may be occasions 55 where rivets will jam and to take care of such instances the clutch mechanism provided by locking dog 45 is disengaged. This enables the drum to be rotated in either direction. By rocking the drum back and forth any jammed rivet is usually 60 lifted clear and returned to the magazine compartment. When the drum has been emptied the lower gate formed by plate 42 is opened to allow the rivets to pass from opening 43 into the compartment. The upper gate 39 is left closed. Thus the rivets that have been in the drum are re- 65 70 75

turned to their proper compartment in the magazine. To substitute rivets of a different size which may be in another compartment of the magazine, the magazine is rotated so as to position the proper compartment underneath the hopper and over opening 43. The gate 42 is then opened which allows the rivets to fall from the compartment into the drum when the magazine frame is in the full line position shown in Fig. 1. In this way a complete change from one size of rivets to another is possible. The change can be effected easily and quickly without danger of spilling or dropping rivets.

A brief résumé of the operation of the machine is as follows: The machine is first loaded by placing rivets of different sizes in the compartments of the magazine. To load a compartment with a given size of rivets a supply of the rivets is first placed in one of the hoppers 32, and the magazine is then rotated about its vertical axis so as to position the desired compartment beneath the outlet from the hopper. The upper gate 39 is then opened and the rivets are permitted to spill or drop from the hopper 32 into the compartment beneath. Obviously, all five compartments of each magazine can be individually loaded with rivets of different sizes in this manner. When the work to be riveted requires a rivet of any given size that compartment of the magazine which contains rivets of this size is positioned over the outlet 43 and the lower gate 42 is opened permitting those rivets which are within the compartment to spill or drop through the outlet 43 into drum 25. The clutch which connects the drum 25 with shaft 17 is then engaged so that whenever the tension member 18 is pulled downwardly to operate punch 12 and shaft 17 is rotated thereby by means of the ratchet 23, 24, the drum will be rotated. The drum serves to feed the rivets through the outlet 53 and into the slot 57 of the track 56. It will be understood that the shanks of the rivets extend through the slot 57 with the heads of the rivets supported by the rails 58. The slot 57 may thus be completely filled with aligned rivets fed thereto by the rotating drum. The rivets are maintained on the track by the escapement mechanism.

The clutch mechanism connecting drum 25 with shaft 17 may be disengaged and the drum rotated freely on the shaft by hand. During such rotation those rivets remaining in the drum and which have not been as yet fed through outlet 53 to the track are returned to the compartment through outlet 43, it being understood that gate 42 is held open during this return. Gate 42 is thereafter closed and the magazine returned from the dotted line position shown in Fig. 1 to the full line position shown in this figure. Thus, all rivets which were in the drum are returned to their respective compartment. The rivet holder may be swung into inoperative position and those rivets which spill from the track may be caught by hand or in a container and returned to hopper 32. The upper gate 39 may then be opened to return these rivets to the same compartment. The magazine may then be turned about its vertical axis to position the compartment containing a new type of rivet or rivet of a different size over the outlet 43. Then by opening the gate 42 the supply of rivets in this compartment can be fed into the drum and fed therefrom onto the track. It will, of course, be understood that only one magazine and its track is used at one time but as each magazine has five compartments and each magazine together with its track may be em-

ployed to feed rivets to the rivet holder at a position with the present machine to use a total of ten different sizes of rivets on the same machine, maintaining suitable supplies of these ten different sizes in their respective compartments, the machine is highly advantageous in that whenever it is desired to change from one size of rivet to a rivet of any of the other nine sizes, the rivets in the drum and on the track can be quickly returned to their respective compartments. In other words, the machine can be very quickly cleared of rivets of one size and rivets of another size substituted therefor.

Various changes may be made in the details of construction without departing from the spirit or scope of my invention as defined in the appended claims.

I claim:

1. In a riveting machine, a track for feeding rivets toward the work, a rotatable drum adapted to receive rivets and feed them into the track, and means providing a magazine for the rivets, said means being associated with the drum and being movable into positions wherein rivets may be optionally emptied from the magazine into the drum or the drum may return rivets into the magazine.

2. In a riveting machine, a track for feeding rivets toward the work, a rotatable drum adapted to receive rivets and feed them into the track, and means providing a magazine rotatable about the axis of rotation of the drum into one position wherein rivets may be fed from the magazine into the drum and into another position wherein the drum may return rivets to the magazine.

3. In a riveting machine, a track for feeding rivets toward the work, a rotatable drum adapted to receive rivets and feed them into the track, and means providing a magazine rotatable about the axis of rotation of the drum into one position wherein rivets may be fed from the magazine into the drum and into another position wherein the drum may return rivets to the magazine, there being a gate between the drum and magazine.

4. In a riveting machine, a track for feeding rivets toward the work, a rotatable drum adapted to receive rivets and feed them into the track, and means providing a magazine rotatable about the axis of rotation of the drum into one position wherein rivets may be fed from the magazine into the drum and into another position wherein the drum may return rivets to the magazine, said magazine having a plurality of compartments, each of which may be selectively placed in communication with the drum.

5. In a riveting machine, a track for feeding rivets toward the work, a rotatable drum adapted to receive rivets and feed them into the track, and means providing a magazine rotatable about the axis of rotation of the drum into one position wherein rivets may be fed from the magazine into the drum and into another position wherein the drum may return rivets to the magazine, said magazine having a plurality of compartments, each of which may be selectively placed in communication with the drum, and a gate common to all compartments controlling the passage of rivets between the drum and any selected compartment.

6. In a riveting machine, a track, a slotted, rotatable drum adapted to receive rivets and feed them into the track, means providing a housing around the drum, and means providing beveled surfaces adjacent the periphery and face of the drum for clearing rivets from the slots of the

drum during its rotation in emptying rivets therefrom.

7. In a riveting machine, a rotatable drum for aligning rivets, means providing a magazine over the drum from which rivets may be fed to the drum, said magazine having a plurality of compartments any of which may be selectively positioned so as to feed rivets to the drum, gate means for controlling the feeding of rivets from a compartment to the drum, and a hopper over the 10 magazine.

8. In a riveting machine, a rotatable drum for aligning rivets, means providing a magazine over the drum from which rivets may be fed to the drum, said magazine having a plurality of compartments any of which may be selectively positioned so as to feed rivets to the drum, and gate 15

means for controlling the feeding of rivets from a compartment to the drum.

9. In a riveting machine, a track, a slotted rotatable drum adapted to receive rivets and feed them into the track, means providing a housing around the drum, and means providing a bevel surface adjacent the periphery of the drum for clearing rivets from the slots of the drum during its rotation in emptying rivets therefrom.

10. In a riveting machine, a track, a slotted rotatable drum adapted to receive rivets and feed them into the track, means providing a housing around the drum, and means providing a bevelled surface adjacent the face of the drum for clearing rivets from the slot of the drum during its rotation in emptying rivets therefrom.

HJALMAR THOMASON.
